ATTORNEY

UNITED STATES PATENT OFFICE.

RAYMOND D. NELSON, OF MOUNT HOORB, WISCONSIN.

SHOE-STRING CLAMP FOR SHOES.

1,412,256.

Specification of Letters Patent. Patented Apr. 11, 1922.

Application filed October 31, 1921. Serial No. 511,898.

To all whom it may concern:

Be it known that I, RAYMOND D. NELSON, a citizen of the United States, residing at Mount Horeb, in the county of Dane and 5 State of Wisconsin, have invented certain new and useful Improvements in Shoe-String Clamps for Shoes, of which the following is a specification.

My invention relates to shoe string clamps 10 for holding the ends of shoe strings within the tops of shoes; and the objects of my invention are, first, to provide a clamp for shoe strings which can be secured between the outside and lining near the top of the 15 shoe, and be opened for inserting the strings, and closed in such a manner that the string ends will be carried below the shoe top, on the inside and concealed from view; second, to provide a clamp that will prevent the 20 strings becoming untied and add very little to the cost of a shoe; and third, to have the device convenient of application in any position around the top of a shoe.

I attain these objects by the mechanism 25 shown in the accompanying drawings in which—

Fig. 1, is a plan, or top view;

Fig. 2, is a front elevation;

Fig. 3, is a side elevation;

30 Fig. 4, is a view of the device inverted;

Fig. 5, shows the clamp attached to a shoe; dotted lines indicate the open position of the clamp in all views.

My device consists of a metal stationary 35 plate 1, with tubular channels, 2, formed on the outer edges from the top downward for a distance, thence to the bottom, and across the bottom the edges are formed into a semi-circular flange 3, the holes 4, through the 40 back are provided for stitching through in

securing the plate to a shoe. A wire clamping loop 5, is slidably disposed in the channels 2, and is turned inward at the lower ends forming stops 6, said loop extends a distance above the plate when the stops rest 45 upon the flange 3, at the bottom. It is obvious that a sliding plate with a hole through it near the top, could be substituted for my loop 5, but I prefer the loop on account of less weight. 50

I apply my device to the top of a shoe at the point desired by making a slight incision in the lining near the top and placing between same and the outer material and securing the stationary plate by stitching or 55 otherwise.

To use the clamp, raise the loop to its highest position and insert the string ends or knots between the loop and top of the plate, then press down the loop, which will 60 securely hold the string and carry it below the shoe top on the inside of same.

Having thus described my invention I claim.

In a device of the kind described, a stationary plate with tubular channels and semicircular flanges down the sides and across the bottom, in combination with a 65 slideable loop disposed in the channels, and means for limiting the movement of the loop 70 up or down in the channels, and means for attaching the stationary plate to a shoe adjacent the top thereof.

In testimony whereof I affix my signature in the presence of two subscribing witnesses. 75

RAYMOND D. NELSON.
